ABSTRACT OF THE DISCLOSURE

A high-voltage mercury-arc rectifier having intermediate electrodes, located at the lower end of the anode chamber between the anode and cathode, and formed as a plurality of spaced truncated cones interfastened by a refractory metal bar. The intermediate electrodes are connected to a voltage divider by terminals which are constructed as hollow bodies containing hollow bolts with slideable rods therein acted on by springs and carrying contact ferrules on one end thereof.

The present invention relates to high-voltage mercury-arc rectifiers, more particularly, to the design of the anode system of a high-power high-voltage mercury-arc rectifier.

There are known high-voltage mercury-arc rectifiers comprising a housing with channels for coolant, an anode chamber, a main anode insulator, an anode, a cathode, intermediate electrodes, a cooler, grids, a filter, excitation anodes, a voltage divider and an evacuation system.

Said high-voltage mercury-arc rectifiers provide power not higher than 3.3 mw. per anode.

It has been proposed before to increase the power by using parallel-connected anodes, but this results in the heavy and bulky design of a rectifier.

The main object of the invention is to provide a high-voltage mercury-arc rectifier which permits an increase of power, and minimizes such phenomena as arcing back and anode and intermediate electrode sputtering while reducing the temperature of the main anode insulator and electrodes.

In accordance with the invention intermediate electrodes are made of monolith truncated cones interfastened by refractory-metal bars having metal shield envelopes and are located in the lower part of the anode chamber. To connect intermediate electrodes with a voltage divider, provision is made for sectional terminals constructed as hollow bolts with a rod and a spring inside, said rod having a contact ferrule at its end, whereas to avoid misfire of the main discharge, the voltage divider is made of low-resistance material. Base insulators which are used to connect cylinders with intermediate electrodes are reinforced with metal caps which are applied by cold compression.

Apart from this, to simplify the design, the main anode insulator is of conical shape.

An embodiment of the invention is given by way of illustration and represented in the accompanying drawings, wherein:

FIG. 1 schematically shows a general sectional view of the high-voltage mercury-arc rectifier;

FIG. 2 is a sectional view of the intermediate electrodes;

FIG. 3 is a sectional view of a terminal adapted to connect a voltage divider with the intermediate electrodes;

FIG. 4 shows the base insulator of the anode unit; FIG. 5 shows the main anode insulator partially broken away;

FIG. 6 shows the anode cooler.

5 The high-voltage mercury-arc rectifier comprises the following main units; housing 1 (FIG. 1), anode chamber 2, main anode insulator 3, anode 4, cathode 5, anode cooler 6, intermediate electrodes 7, grids 8, filter 9 with cone 10, excitation anodes 11, voltage divider 12 and evacuation system 13 equipped with high-vacuum cock 14.

10 Referring to FIG. 1, anode chamber 2 is fixed on the upper flange of housing 1 and provided with cooling ribs 15. Main anode insulator 3, in its turn, is mounted on the upper plate of anode chamber 2. Terminals 16 of excitation anodes 11 as well as other terminals of auxiliary electrodes (not shown in FIG. 1) extend through the lower plate of anode chamber 2. To maintain a vapor-dynamic mode for the rectifier, there are formed in

15 housing 1 channels 17 for the circulation of coolant. A cathode cap 18 is provided with double walls between which coolant circulates for the same purpose. To maintain the temperature conditions of anode insulator 3 within the required limits and at high load, intermediate electrodes are extended into the lower part of anode chamber 2, for which purpose cylinders 19 having electrodes 7 in their lower parts are correspondingly elongated.

20 The intermediate electrodes are formed by a plurality of spaced truncated cones 20 (FIG. 2) whose spacing increases the greater the distance from the axis of the rectifier, thereby providing for a uniform current density throughout the entire surface of the end part of anode 4. To increase the mechanical strength of electrodes 7, cones 20 are assembled on bars 21 made of refractory metal, for instance molybdenum. The external surfaces of bars 21 are protected against molybdenum sputtering by iron castings 22. Voltage divider 12 (FIG. 1) is connected with cylinders 19 of intermediate electrodes 7 by sectional terminals 23. Each of the terminals 23

25 comprises a hollow bolt 24 (FIG. 3) with shoulders 25, said bolt being passed through a hole in anode insulator 3; contact rod 26 with ferrule 27 at its end; and spring 28. Bolt 24 is pressed against insulator 3 through metal packing 29 with the aid of nut 30 and spring 31. The end of the hole in bolt 24 is closed by plug 32 and sealed by a vacuum-tight weld. Ferrule 27 is pressed against anode cylinder 19 with spring 28.

30 From the outside, terminal 23 receives active voltage divider 12 (FIG. 1) serving to remove negative charges 40 from intermediate electrodes 7 and to sharply reduce the probability of misfire of the main discharge. Voltage divider 12 is made of low-resistance material, i.e. material with a resistance value at which the time constant of a circuit comprising the above-mentioned divider and the capacitance between anode cylinders 19 is not more than a frequency cycle of the mains. Base insulators 33 with cylinders 19 fixed on them are reinforced with metal caps 34 (FIG. 4). Caps 34 are fixed to insulators 33 by cold compression, which considerably simplifies

35 45 50 55 60 65 70 75 80 85 90 95 and cheapens the manufacturing process, as compared to the conventional practice of expensive silver soldering of the caps in a vacuum.

The surface of conventional anode insulators of high-voltage mercury-arc rectifiers is of a step-like shape which causes technological difficulties in surface polishing. To simplify a technological processing and assembling of the rectifier, the internal surface of main anode insulator 3 is made conic in shape (FIG. 5). This shape of the anode insulator provides for the necessary intervals between the above-mentioned insulator and the elements of the anode unit.

The anode cooler is of the conventional design of a system of pipes.

The cooler 6 (FIGS. 1, 6) is made as a closed hollow body with radiator 35 in its upper part. When cooler 6 operates, mercury starts boiling at its bottom 36 and the vapors produced in the body go up and condense in radiator 35.

The above-described design of the anode system of a high-voltage mercury-arc rectifier permits to increase the load up to 7.5 mw.

What is claimed is:

1. A high-voltage mercury-arc rectifier comprising a housing having channels for the passage of a coolant; a cooled cathode cap located inside said housing; an anode chamber mounted on said housing; a main anode insulator fixed on said anode chamber; a cathode located in the bottom of said housing; a hollow anode located inside said anode chamber and main anode insulator; an anode cooler located inside said anode; cylinders located inside said anode insulator and anode chamber; intermediate electrodes assembled of truncated cones interfastened with refractory-metal bars with metal shield envelopes, said intermediate electrodes being fixed into said cylinders and located in the lower part of said anode chamber between the cathode cap and anode; a filter located inside said housing between the cathode cap and intermediate electrodes; grids located between said intermediate electrodes and filter; excitation anodes located in said housing; a voltage divider and terminals connecting said voltage divider with said cylinders, said terminals being passed through holes provided in said anode insulator; and an evacuation system mounted on said housing.

2. A rectifier as claimed in claim 1 wherein each of

said terminals comprises a hollow body, a rod in said body including a contact ferrule on one end thereof and a spring acting on the rod.

3. A rectifier as claimed in claim 1 comprising a capacitor connected between the divider and each cylinder, said voltage divider having a resistance value such that the time constant of a circuit comprising said divider and the capacitance between said cylinders is not more than a frequency cycle of the mains.

4. A rectifier as claimed in claim 1 comprising base insulators for the support of said anode cylinders, said base insulators including reinforcing metal caps which are cold pressed on said insulators.

5. A rectifier as claimed in claim 1 wherein said main anode insulator is of conical shape.

6. A rectifier as claimed in claim 1 wherein said anode cooler is a closed hollow body partially filled with mercury.
